(57) **CLAIM**

(21) Appl. No.: **29/287,446**

The ornamental design for a clip for protecting automobile parts, as shown and described.

(22) Filed: **Aug. 9, 2007**

DESCRIPTION

(30) **Foreign Application Priority Data**

Feb. 9, 2007 (JP) 2007-003087

FIG. 1 is a perspective reference view of the front, left side and top of a clip for protecting automobile parts showing our new design;

(51) **LOC (9) Cl.** 12-06

FIG. 2 is a front view thereof;

(52) **U.S. Cl.** D12/223

FIG. 3 is a rear view thereof;

(58) **Field of Classification Search** D12/223;
D8/349, 394; 248/231.81

FIG. 4 is a top plan view thereof;

See application file for complete search history.

FIG. 5 is a left side view thereof;

(56) **References Cited**

FIG. 6 is a right side view thereof; and,

FIG. 7 is a bottom view thereof.
